TESTING ARRANGEMENT FOR FINDER SWITCHES IN TELEPHONE SYSTEMS

John William McClew and Owen Avis Pearce,
Liverpool, England, assignors to Automatic
Electric Laboratories Inc., Chicago, Ill., a cor-
poration of Delaware

Application December 8, 1944, Serial No. 567,224
In Great Britain February 18, 1944

9 Claims. (Cl. 179—18)

1

The present invention relates to finder switch arrangements suitable for use in telephone or like electrical signalling systems, and is more particularly concerned with improvements in arrangements by means of which a marked line can be connected to equipment of different classes all serving a number of such lines.

In private automatic exchange or private automatic branch exchange telephone systems of the line finder type a number of finder/connector links are usually provided and are allotted for use under control of one or more common equipments. Calling lines gain access to these so-called local links via the finder portions of the links which hunt for line markings having finder bank positions characteristic of the calling subscribers concerned. Subsequently, in response to dialled digits characteristic of local subscribers, the connector portions of the links effect local automatic connections. In response to certain other characteristic dialled digits, other finder switches may be started up to connect the calling subscribers concerned direct to special service links.

A typical special service link connection occurs where two private exchange boards are linked by a tie line. In this case a calling subscriber on one board wishing to gain access to a subscriber on the other board will first dial a characteristic prefix digit or digits in response to which the local link taken into use will cause the tie line link to connect itself over a finder switch with the calling party, the local link then being released for further common use. The tie line link on being switched through to the calling subscriber will cause a local link on the other board to connect with the distant end of the tie line and further dialled digits which will extend into the tie line link will be repeated to the distant local link to effect connection with the required party. Another example, which occurs particularly on private automatic branch exchange boards, is the association of a main exchange line link with a calling subscriber's line.

With regard to the various finding conditions involved, a normal calling line marking will appear on the multiplied local link finder switch test banks, while the line marking for subscribers requiring special services will also appear in this multiple unless the test conditions for the finder switches of each of the special services provided for are segregated from the normal calling line test conditions. This latter method is, however, not always desirable or even feasible owing to the additional equipment required which will usu-

2

ally involve extra banks and wipers on the local link finder and connector switches.

If the other arrangement is adopted whereby the test conditions for more than one type of finding operation can appear together in the local link finder switch test bank multiple, the question of possible cross switching will naturally arise. Arrangements have already been proposed whereby test conditions for two differing types of finding operation may appear simultaneously in a common bank multiple without danger of cross switching of the finder switches concerned.

When test conditions for three differing types of finding operation are likely to arise however, it has hitherto been thought essential to ensure that only one type of finding operation can take place at a time, which necessarily introduces delay particularly at busy calling periods when it is at least desirable.

It is an important object of the present invention to provide arrangements permitting three differing types of finding operation to take place simultaneously under conditions of the above-mentioned character without any risk of wrong connection resulting.

According to one feature of the invention, in a finder switch arrangement suitable for use in telephone or like signalling systems, the operation of a finder to connect with a marked one of a group of lines is under control of a double-wound relay not operative on either winding alone, one winding of the relay being connected in the marking circuit to potential of one polarity while the other winding is connected to the switch wiper and to potential of opposite polarity whereby separate markings of either polarity may be used to control the simultaneous operation of other classes of finders having access to the same lines.

According to another feature of the invention, in a finder switch arrangement suitable for use in telephone or like signalling systems and having similar finders of three different classes adapted to hunt simultaneously over a group of lines for markings respectively characteristic of the class of finder, for the first class the marking comprises potential of one polarity applied over a wiper of a finder of the third class, for the second class the marking comprises potential of the other polarity also applied over a wiper of a finder of the third class and for the third class the marking comprises potential of the one polarity applied through the winding of a double-wound relay which is not operative on either winding alone the other winding of the relay being connected

to potential of the first polarity and to the switch wiper.

A further feature of the invention is that in a finder switch arrangement suitable for use in telephone or like signalling systems and having similar finders of three different classes adapted to hunt simultaneously over a group of lines for markings respectively characteristic of the class of finder, the finders of two of the classes being set in operation in response to a suitable signal transmitted over a calling line to which connection has already been made by a finder of the third class, the test banks of finders of the said two classes are directly multipled and are connected to the test banks of finders of the third class over back contacts of the line relays of the associated lines while marking of a calling line in the banks of the third class of finders is effected over front contacts of the said relays whereby marking potential applied to the test banks of finders of the third class is not effective in the test banks of the finders of the other two classes.

The invention will be better understood from the following description of one method of carrying it into effect, reference being had to the accompanying drawing which shows a basic circuit of the test conditions which obtain on a P. A. X or P. A. B. X board of the above-mentioned type if two special service finder switches happen to be hunting for particular subscribers' lines at the same time as a local link finder switch is hunting for an ordinary calling line.

In the circuits typical values for the test relay windings and for the various resistances are given for general guidance.

LL₁—LL₃ represent certain parts of the local finder/connector links such as the local finder connector links described in Patent No. 2,087,930, granted July 27, 1937, to John H. Voss, and in these links 1FSI—3FSI represent the test wipers and banks of the uniselector finder switches 1CS1—3CS1 represent wipers and banks of the two-motion connector switches, while 1X1—3X1 are contacts of switching relays within the links, contacts 1X1 and 2X1 being shown in operated condition. Contacts 2L1, 5L1 and 10L1 are marking contacts of the well-known line relays of three subscribers which will be referred to as lines 2, 5 and 10.

Local links LL₁ and LL₂ are assumed to have associated themselves with subscribers Nos. 2 and 5 respectively, the line relays of which only the contacts 2L1 and 5L1 are shown and which will have been released in response to the operation of the associated cut-off relays (not shown) in well known manner responsive to the connection of the local finder connector links thereto. The connector switches in these links are moreover assumed to have been set by dialling to positions which would cause the finder switch AFS of special service link SAL to hunt for subscriber No. 2 and which would cause finder switch BFS of special service link SBL to hunt for subscriber No. 5.

The special service links SAL and SBL represent certain parts of two way trunk circuits and associated finder switches such as those in the Voss Patent 2,087,930. While only one special service link SAL is shown and only one special service link SBL is shown it may be understood that there is a group of special service links such as the link SAL and another group of special service links such as the link SBL. Allotting equipment, which may be similar to the allotting equipment AE, is provided for each group so that an idle link in

each special service group is preselected for operation in the well known manner.

As regards link LL₃, this is assumed to be finding an ordinary calling subscriber No. 10, the line relay contacts 10L1 of which will be operated as shown. As is usual practice, the finder switch in link LL₃ is assumed to be operated under the control of allotting equipment AE which includes the allotting switch AS, the wipers of which will connect up with link LL₃. In the allotting equipment the usual test relay which is usually of similar character to relays SA and SB has been replaced by a shunt field relay for reasons which will be appreciated later.

Reviewing the operation of the link LL₃ finder switch, the switch magnet 3FM will be operated in a self-interrupted circuit via its contacts 3FMC, lead 14, bank and wiper AS2 and contacts LT1 to earth so that it will advance the switch wipers including the test wiper 3FSI in a counter-clockwise direction as shown. Wiper 3FSI connects via normal contacts 3X1, lead 15, and bank and wiper AS3 with the earthed righthand winding of the shunt field relay LT, while the subscriber No. 10 line marking on the finder switch bank comprises resistance battery via the left-hand winding of relay LT which extends via resistance YC, lead 12 which is preferably common to all the subscribers served by the finder switches shown and operated line relay contacts 10L1 on to a characteristic position on bank 3FSI.

When wiper 3FSI reaches the line marking, the two windings of relay LT are energised in series and under this condition relay LT rapidly operates, as verified by experiment with the resistance values indicated, and opens the switch magnet driving circuit at contacts LT1. At the same contacts it extends earth over wiper and bank AS1 to lead 13 so as in known manner to initiate the operation of a switching relay (not shown) which at its contacts 3X1 switches the test lead from wiper 3FSI through to wiper 3CS1 and at other contacts (not shown) connects the calling line over other finder switch banks and wipers through to the link circuit in readiness for the reception of dialled digits. It will be understood that the operation and subsequent holding of the subscriber's cut-off relay is effected over another bank and wiper of the finder switch.

Owing to the shunt field magnetic circuit of relay LT, this relay will only operate when both its windings are simultaneously energised in a predetermined direction, and hence it will only operate in the circumstances described.

Considering now the operation of the finder switch AFS in the special service link SAL which is searching for subscriber No. 2, the line marking will comprise an earth potential which is applied to a characteristic position in bank AFS1 via the low resistance winding of the test relay SA in link SAL, connector switch bank and wiper 1CS1 of the local link LL₁, contacts 1X1, finder switch bank and wiper 1FSI and line relay contacts 2L1.

When wiper AFSI reaches this marking, relay SA will rapidly operate in series with the battery connected resistance YA and at contacts SA1 will open the magnet driving circuit and will extend earth over lead 10 to initiate the switching through of the calling line No. 2 to the link SAL in known manner.

With regard to the operation of the finder switch BFS in link SBL which is searching for subscriber No. 5, the line marking in this instance will comprise a battery potential which is applied

to bank **BFS!** via resistance **YB**, bank and wiper **2CS!** in link **LL2**, contacts **2XL**, wiper and bank **2FS!** and contacts **5L1**.

When wiper **BFS!** encounters this marking, relay **SB** will rapidly operate in series therewith and will function in similar manner to relay **SA**. By virtue of the low resistance of relay **SB** an immediate guard is placed on the outlet seized and the adjustment of the relay is moreover such that once it has operated, if another similar test relay connects itself in parallel it will continue to hold while the second relay will fail to operate.

Consideration will now be given to the possibilities of cross switching when two or three of the finder switches such as **AFS**, **BFS** and **3FS** of the differing kinds of links **SAL**, **SBL** and **LL3** are searching simultaneously for subscribers Nos. 2, 5 and 10 respectively.

With regard to possible cross switching between links **SAL** and **SBL**, if resistances **YA** and **YB** have values such as 400 ohms and 150 ohms respectively, relay **SA** is adapted to operate in series with 400 ohms, and relay **SB** is adapted to operate in series with 150 ohms and not to operate in series with 400 ohms. Link **SAL** can never switch in to the 150 ohm battery comprising the marking for subscriber No. 5, since as it is not connected to the wiper of its associated finder relay **SA** can never encounter such marking. Conversely, link **SBL** can never switch in to the 400 ohm battery connected to the link **SAL** finder switch wiper **AFS!**, since this constitutes a non-operate condition for relay **SB**.

Cross switching between either of the links **SAL** or **SBL** and local link **LL3** is impossible since the subscriber No. 10 battery marking comprising the 11 ohm battery-connected winding of relay **LT** in series with the 120 ohm resistance **YC** can never be encountered by either relay **SA** or **SB**. Thus as regards link **SAL** the finder switch wiper **1FS!** of local link **LL1** through which the test relay **SA** is connected up will be stationary and positioned as shown where it connects with the calling line relay contacts **2L1** of subscriber No. 2, and hence relay **SA** can never meet subscriber No. 10 marking, while as regards link **SBL** the subscriber No. 10 marking is prevented from extending to the **BFS!** bank by virtue of the respective connections to the back and front contacts **10L1** of the line relay.

As regards the local link **LL3**, this cannot possibly switch in to the marking of either of the special service calling subscribers Nos. 2 and 5, since as previously mentioned the test relay **LT** will only operate when both its windings are energised in series.

Hence in the above-described manner as many as three differing types of links can simultaneously hunt for the appropriate lines in the same group and each is assured of switching in only to a specific line circuit.

What we claim as new and desire and secure by Letters Patent is:

1. In a telephone system, a line, a finder switch having a bank and a movable wiper therefor, a double wound shunt field relay for controlling the movement of said wiper, said relay being operative only in response to the energization of both of its windings, a marking contact for said line in said bank, means for energizing both of said windings upon the engagement of said wiper with said marking contact to operate said shunt field relay thereby stopping the movement of said wiper.

2. In a telephone system having a plurality of lines, a finder switch having a wiper, marking contacts for said lines accessible to said finder, a double wound relay operative only in response to the energization of both of its windings, means for connecting a potential of one polarity through one winding of said relay to the marking contact of an individual one of said lines, means for connecting a potential of opposite polarity through the other winding of said relay to said wiper, said relay operative upon the engagement of said wiper and said last marking contact to control the movement of said finder.
3. In a telephone system having a plurality of lines, a first group of finders, a second group of finders, a third group of finders, marking terminals for said lines in each of said three groups of finders, means for applying a potential of one polarity to the marking terminals of any one of said lines for stopping the movement of one of the finders of said first group, means for applying a potential of the opposite polarity to the marking terminals of any one of said lines for stopping the movement of one of the finders of said second group, a double wound shunt field relay operable only in response to the energization of both of its windings, means for connecting the marking terminals in said third group of finders for any one of said lines to a potential of said opposite polarity through one of the windings of said relay, means for connecting a potential of said one polarity to a wiper of one finder of said third group of finders through the other winding of said relay, said relay operative upon the engagement of said wiper with one of said last marked terminals to stop the movement of said one finder of said third group, means for permitting simultaneous operation of finders in each of said groups, and means for stopping a finder of any one of said groups only in response to a marking for that group.
4. In a signalling system, a group of finder-connector links, switching contacts and a wiper in each link, a first group of finders, a second group of finders, a plurality of lines, marking terminals for said lines accessible to the finders of said links and accessible to the finders of said two groups, means for establishing markings of three different classes and for connecting said markings to different ones of said marking terminals, one of said classes of markings effective for stopping finders of said first group on marking terminals to which said one class of marking is connected, another of said classes of markings effective for stopping finders of said second group on marking terminals to which said other class of marking is connected, and the last of said classes of markings effective for stopping finders of said links on marking terminals to which said last class of marking is connected, means for permitting simultaneous searching by finders of said links and by finders of said two groups, means including the switching contacts and the wiper of one of said links for stopping the finder of said one link only on a terminal marked for said group of finder-connector links, means including the switching contacts and the wiper in another of said links for stopping one of said first group of finders only on a terminal marked for said first group, and means including the switching contacts and the wiper of a further one of said links for stopping one of said second group of finders only on a terminal marked for said second group.
5. In a telephone system wherein similar find-

ers of three different classes have access to the marking contacts of a plurality of lines, means for permitting finders of said three different classes to hunt simultaneously over at least a portion of said marking contacts, a source of potential having terminals of two polarities, wipers on said finders, means for connecting a distinctive marking for one of said classes of finders to marking contacts of any one of said lines over a wiper of one of the finders of another of said classes, said marking including potential of one of said polarities, means for connecting another distinctive marking for a further one of said classes of finders to marking contacts for any one of said lines over the wiper of another finder of said other class, said other distinctive marking including potential of the other of said polarities, a double wound relay operative only in response to the energization of both of its windings, means for connecting a further distinctive marking for said other class of finders to marking contacts of any one of said lines, said further marking including potential of said one polarity and one winding of said relay, and means for connecting potential of said other polarity through the other winding of said relay to the wiper of a further one of said finders of said other class, said relay operative in response to the engagement of said last wiper with one of said last marked contacts.

6. In a switching system wherein the wipers of similar finders of three different classes hunt simultaneously over marking contacts for a plurality of lines, means for connecting a characteristic marking to a marking contact of one of said lines to control the movement only of a finder of one of said classes, said means including a wiper of a finder of another one of said classes, means for connecting a different characteristic marking to a marking contact of another of said lines to control the movement only of a finder of a further one of said classes, said means including a wiper of another finder of said other class, means for connecting a still different characteristic marking to a marking contact of a further one of said lines to control the movement only of a finder of said other class.

7. In a signalling system, finders of three different classes, a plurality of lines having test terminals accessible to each of said finders, wipers on said finders, means for permitting the wipers of finders of said three classes to hunt simultaneously over said test terminals, a source of potential having two polarities, characteristic markings of three different classes, means for connecting a characteristic marking of one of said classes to test terminals of one of said lines over a wiper of a finder of one of said classes, said marking including potential of one of said polarities, means responsive to said marking for stopping only a finder of another of said classes on a test terminal of said one line, means for connecting another characteristic marking of another of said classes to test terminals of another one of said lines over a wiper of another finder of said one class, said other marking including potential of the other of said polarities, means responsive to said other marking for stop-

ping only of a finder of a further one of said classes on a test terminal of said other line, a double wound relay operative only in response to the energization of both of its windings, means for connecting a characteristic marking of a further one of said classes to test terminals of a further one of said lines, said last marking including one winding of said relay and potential of said other polarity, means for connecting potential of said one polarity to a wiper of a further finder of said one class, said relay operative in response to the engagement of said last wiper and one of said last test terminals to stop only said last finder on a test terminal of said last line.

15 8. A plurality of lines, marking contacts for each line, a plurality of finder groups, test terminals for each line in each finder group, a different characteristic marking for each finder group, the individual marking contacts of any one of said lines operable in one manner to connect the test terminals of said line in only one of said finder groups to the characteristic marking for the same, thereby stopping the movement 20 only of a finder in said one group on a test terminal of said one line, said individual marking contacts operable in another manner to connect said test terminals to the test terminals for said line in the other finder groups, means for connecting the characteristic marking for anyone of said 25 other finder groups to said test terminals, means for stopping the movement only of a finder of said one other group on a test terminal of said line, and means for permitting simultaneous operation of a finder in each of said finder groups.

9. A group of finders, a characteristic marking for said finder group, a line having test terminals accessible to finders of said group and having marking contacts operable for connecting 40 said test terminals to said characteristic marking, means including said characteristic marking for stopping a finder of said group on a test terminal of said line, other groups of finders, test terminals for said line accessible to finders of said other groups, different characteristic markings for each of said other groups, said marking contacts operable in case a finder of said first group is stopped on a test terminal of said line to connect the test terminals accessible 45 to finders of said group to the test terminals accessible to finders of said other groups, means for connecting the characteristic marking for any one of said other groups to said test terminals, and means including said last characteristic 50 marking for stopping only a finder of said one other group on a test terminal of said line.
